CODED TRACK CIRCUIT SIGNALING SYSTEM WITH IMPROVED FEED-BACK CODE CIRCUITS

Arthur L. Jerome, Edgewood, Pa., assignor to Westinghouse Air Brake Company, a corporation of Pennsylvania

Application March 6, 1947, Serial No. 732,866

10 Claims. (Cl. 246—38)

1

My invention relates to railway signaling systems, and particularly to an improved railway signaling system of the coded track circuit type.

In coded track circuit systems, in addition to the use of a master code of various frequencies, which is transmitted from one end of the section to a track relay at the other end of the section, there is sometimes provided a feed back code which energizes a code following or track relay at the feed end of the section by impulses of feed back energy transmitted during the "off" periods of the principal or master code.

As usually arranged, the code following or track relay at the feed or exit end of the section which responds to the impulses of feed back energy is intermittently connected across the rails of the section by the code transmitting relay. Should extraneous or foreign energy be supplied to the track rails, of the proper polarity and value to operate this feed back track relay, the feed back track relay will respond to such energy if it is alternately connected to and disconnected from the section rails by the code transmitting relay.

It will be seen, therefore, that if in the presence of foreign current the transmitting relay for the master code operates to cause a false coding action of the feed back track relay intended to respond only to impulses of feed back energy transmitted from the other end of the track circuit, it might create an unsafe condition if the feed back code is relied upon for safety.

This condition is protected against by requiring that the feed back track relay be released before a pulse of master code energy may be transmitted. It follows that if the feed back track relay is improperly energized, it will remain energized with the result that the supply of master code impulses is interrupted, and the coding in both directions is stopped, putting to stop the signal controlled by the master code and thus showing that an abnormal condition exists.

Where the equipment is arranged so that an impulse of master code cannot be supplied to the track rails until the feed back track relay releases a delay in supplying the impulses of feed back energy to the section rails during the "off" periods of the master code may delay the start of the "on" periods of the master code with the result that the impulses of master code are objectionably reduced in length. In order to eliminate this delay in the supply of impulses of master code to the track rails the equipment may be arranged to apply the impulse of feed back energy to the section rails immediately upon the release of the track relay which responds to the master

2

code. However, if these impulses of feed back energy are short enough to avoid distortion of the "on" time of master code of the highest frequency, the periods between impulses of feed back energy are substantially longer than the "on" periods of the feed back energy when the master code is of low frequency. This results in an unequal operating cycle of the track relay which is operated by the feed back energy and interferes with the operation of the decoding means governed by this track relay.

It is an object of my invention to provide an improved type of coded track circuit signaling system in which the contacts of the track relay which respond to feed back energy are maintained in one position substantially as long as they are maintained in their other position.

Another object of my invention is to provide an improved type of coded track circuit in which the apparatus for supplying impulses of feed back energy incorporates various safety and self-protecting features.

An additional object of my invention is to provide an improved means for highway crossing warning signal control which may be used with coded track circuit signaling systems.

A further object of my invention is to provide for the track relay which responds to feed back energy an improved stick circuit which holds the relay contacts picked up throughout the "off" periods in the master code and is arranged so that it does not interfere with the control by this track relay of the transmitter relay.

Another object of my invention is to provide in a track circuit of the type described a feed back track relay having pick up and holding windings the circuits of which are independently controlled in such manner that the circuit of the pick up winding is interrupted only after the relay contacts release while the circuit of the holding winding is interrupted at the end of each "off" period in the master code regardless of whether or not the relay contacts release.

A further object of the invention is to provide an improved coded track circuit of the type described which incorporates means for checking operation of the decoding means associated with the track relay.

In practicing my invention, I arrange the equipment at the entrance end of the track section so that the impulses of feed back energy are supplied to the track rails immediately upon release of the track relay. The feed back control means comprises a slow release relay which is energized by current supplied over a front con-

tact of the track relay and when picked up establishes a circuit including a back contact of the track relay for supplying energy to the track rails. The track relay when picked up establishes a stick circuit for itself while the means for detecting code following operation of the track relay is governed by a contact of the track relay and also by contacts of the slow release relay so as to prevent improper energization of the decoding means in the event the contacts of the track relay or the stick circuit for the track relay are defective. At the exit end of the track section a transmitting relay is provided and has contacts which control connection of the track battery and of the winding of a feed back track relay with the track rails. The circuit of the transmitting relay is governed by a back contact of the feed back track relay so that the contacts of the transmitting relay can be operated to interrupt the circuit of the feed back track relay only when the contacts of this relay are released. The feed back track relay when picked up establishes for itself a stick circuit governed by the code transmitter which governs the transmitting relay to thereby keep the feed back track relay contacts picked up until the end of the "off" period in the master code and thereupon leaving it connected across the track rails so that it will release only if foreign current is not present.

In a track section approaching a highway intersection I provide means for operating the slow release repeater relay for the track relay to thereby supply energy to the track rails to discontinue operation of the crossing signals when the approach section is vacated.

I shall describe four forms of coded track circuit signaling systems embodying my invention, and shall then point out the novel features thereof in claims.

In the drawings,

Fig. 1 is a diagrammatic view of a section of railway track equipped with a coded track circuit signaling system embodying my invention,

Fig. 2 is a fragmentary view of a modification of a portion of the equipment shown in Fig. 1,

Fig. 3 is a diagrammatic view of a section of railway track equipped with a coded track circuit signaling system embodying my invention for controlling a highway crossing warning signal, and

Fig. 4 is a fragmentary view of a modification of a portion of the equipment shown in Fig. 3.

In the drawings similar reference characters refer to similar parts in each of the several views.

Referring to Fig. 1, there is shown therein a section of railway track T having track rails 1 and 2 which are isolated from the rails of the adjacent section by the usual insulated joints 3. Traffic normally moves through this section in the direction indicated by the arrow, that is, from left to right. A signal S, which as shown is of the color-light type having a green lamp G, a yellow lamp Y, and a red lamp R, is located at the left-hand or entrance end of the section T and governs movements of traffic into the section T.

The signal S is controlled by master code energy fed from the exit end of section T, and it is assumed that at the exit end of section T it is desired to provide a relay which is responsive to the occupancy of the section T.

The equipment at the entrance end of section T comprises a code following track relay TR, which is of a type the contacts of which are biased to their lower released position and pick up when and only when energy flows through the winding

in the direction indicated by the arrow, that is, from right to left; an auxiliary code following relay TP, which is of a type the contacts of which are slightly slow in releasing; slow acting relay FSA and slow release relay BSA which detect code operation of the track relay TR and repeater relay TP; a decoding relay DR which is supplied with energy from a decoding unit 180DU; a decoding transformer DT; and a feed back battery FB.

At the exit end of section T, the equipment comprises a feed back code following relay K which is of a type similar to the track relay TR; a code transmitting relay CTM; code transmitters 180CT and 75CT; slow release relays KA and KB which detect code operation of relay K; a control relay CR; and a track battery TB.

At each end of section T, in addition to the apparatus listed above, there is provided a source of direct current, not shown, whose positive and negative terminals are denoted as B and C, respectively.

The equipment is shown in the drawings in its normal condition, with track section T unoccupied. Code transmitters 180CT and 75CT operate continuously, the contacts of code transmitter 180CT being operated at a frequency of 180 complete cycles per minute, while the contacts of code transmitter 75CT are operated at a frequency of 75 complete cycles per minute. As shown, the control relay CR, which may be controlled in any suitable manner by traffic conditions in advance of section T, is picked up and when the contacts of code transmitter 180CT pick up, a circuit is established to supply energy to the relay CTM. This circuit is traced from terminal B, over back contact 10 of relay K, which at this time is released, over front contact 12 of relay CR, over front contact 14 of code transmitter 180CT, and through the winding of relay CTM to terminal C.

As a result contact 16 of relay CTM picks up and establishes a circuit for supplying energy to track relay TR over the section rails 1 and 2. This circuit is traced from the positive terminal of battery TB, over front contact 16 of relay CTM, through the winding 18 of relay K from right to left, over section rail 1, through the winding of relay TR from right to left, over back contact 20 of relay TR, over back contact 22 of relay TP, and over section rail 2 to the negative terminal of battery TB.

Accordingly, the track relay TR picks up and its back contact 20 interrupts the circuit traced above for supplying energy to the relay winding. However, the characteristics of this relay are such that when it is energized by energy of sufficient value to cause the relay to open its back contacts, the contacts will continue to move to their other position. When contact 20 of relay TR picks up, it by-passes contact 22 of relay TP and establishes a direct connection to track rail 2 for supplying energy to the winding of relay TR.

When contact 24 of relay TR picks up, it establishes a circuit for supplying energy to the winding of relay TP. This circuit is traced from terminal B, over front contact 24 of relay TR, and through the blocking rectifier R1 and the winding of relay TP to terminal C. When the contacts of relay TP pick up, contact 22 picks up and thereby connects the negative terminal of battery FB to section rail 2. However, the positive terminal of the battery FB remains disconnected at this time since contact 20 of relay TR is picked up.

After a time interval, contact 14 of code transmitter 180CT releases, interrupting the circuit for supplying energy to relay CTM, which thereafter releases. When contact 16 of relay CTM releases, it interrupts the supply of energy from battery TB to the section rails 1 and 2 and effectively connects the winding 18 of relay K across the section rails 1 and 2.

When the supply of energy from the battery TB is interrupted, relay TR releases and its contact 24 interrupts the supply of energy to relay TP. Relay TP is slightly slow in releasing its contacts, and when contact 20 of relay TR closes in its released position a circuit is established for supplying a short impulse of feed back energy from battery FB to the relay K over section rails 1 and 2. This circuit is traced from the positive terminal of battery FB, over back contact 20 of relay TR, through the winding of relay TR from left to right over section rail 1, through the track or pick up winding 18 of relay K from left to right, over back contact 16 of relay CTM, over section rail 2, and over front contact 22 of relay TP to the negative terminal of battery FB. When relay TP releases, the circuit traced above for supplying the feed back energy to relay K is interrupted by contact 22 of relay TP. The relay TP is selected so that its release time is shorter than the intervals between the impulses of master code energy.

Accordingly, the relay K receives a short impulse of energy flowing in such a direction that its contacts will pick up. When contact 18 of relay K closes in its picked-up position, it establishes a stick circuit for maintaining the relay K energized until the code transmitter 180CT again picks up its contacts. This circuit is traced from terminal B, over front contact 10 of relay K, over front contact 28 of relay CR, over back contact 30 of code transmitter 180CT and through the holding winding 32 of relay K to terminal C. As a result, when the relay K picks up its contacts in response to an impulse of feed back energy, the relay contacts will remain picked up until such time as code transmitter 180CT again picks up its contacts.

After a time interval, code transmitter 180CT again picks up its contacts, thereby interrupting the circuit previously traced for maintaining the holding winding 32 of relay K energized, whereupon relay K releases. Upon the release of relay K, its back contact 10 reestablishes the circuit originally traced for supplying energy to the relay CTM, and the cycle of operation described above is repeated.

It will be seen, therefore, that with the track section T unoccupied and the control relay CR energized, impulses of master code energy are supplied to relay TR 180 times per minute and the contacts of relay TR pick up and release 180 times per minute. Relay TP also operates its contacts at the same rate, but its contacts are slightly slow in releasing and each time that relay TR releases its contacts, an impulse of feed back energy is immediately supplied to relay K for a period determined by the release time of relay TP. When relay K is picked up by an impulse of feed back energy, its contacts are maintained in their picked-up position until the end of the impulse supplied over the track rails and also are maintained in their picked-up position by the relay holding winding until the next impulse of master code energy is to be transmitted, at which time it is necessary that the relay K release in order that the relay CTM

can pick up to supply an impulse of master code energy to the rails of section T.

Since the impulses of feed back energy are supplied to the track rails immediately upon release of the track relay these impulses may be long enough to insure that relay K will pick up, and at the same time will terminate soon enough to permit relay K to release immediately upon interruption of the circuit of the relay holding winding. This eliminates distortion of the impulses of master code which might occur if after release of the track relay there is any delay in the supply of feed back energy to the track rails.

15 The relay FSA is energized each time contact 24 of relay TR and contact 34 of relay TP are picked up. Energy is supplied to relay FSA over the circuit which is traced from terminal B, over front contact 24 of relay TR, over front contact 34 of relay TP, and through blocking rectifier R2 and the winding of relay FSA to terminal C.

20 Blocking rectifiers R1 and R2 serve to isolate the relays TP and FSA insofar as counter electromotive force generated by the relays upon interruption of their energizing circuits is concerned.

25 When contact 24 of relay TR releases, energy is supplied to relay BSA over the circuit which is traced from terminal B, over back contact 24 of relay TR, over back contact 36 of relay TP, over front contact 38 of relay FSA, and through the winding of relay BSA to terminal C.

Accordingly, it will be seen that while the contacts of relays TR and TP are following code, the 30 relays FSA and BSA are alternately energized and their contacts will pick up and remain picked up at this time, since the relays are slow enough in releasing to bridge the intervals in the supply of energy thereto. Thus the relays 35 FSA and BSA are energized and their contacts are picked up when and only when the track relay TR and its repeater relay TP are responding to coded energy. If the track relay TR or its repeater relay TP ceases to operate and its contacts remain continuously released or continuously picked up, the supply of energy to relay BSA will be interrupted, and its contacts will release after its release time has expired.

Similarly, since relay K is at this time following 40 the impulses of feed back energy, relay KA is energized each time that contact 40 of relay K is picked up, and when contact 40 of relay K releases energy is supplied over a front contact 42 of relay KA to the winding of relay KB, which picks up its contact 44 to establish the 45 supply of energy to the approach controlled circuit governed thereby. Accordingly, the relays KA and KB detect the code following operation of relay K in a manner similar to that in which 50 relays FSA and BSA detect the code following operation of relay TR.

As pointed out above, after the contacts of relay K are picked up by an impulse of feed back energy supplied over the track rails during an 55 "off" period in the master code, they are maintained picked up for the remainder of the "off" period by energy supplied to the relay holding winding. Accordingly, contact 40 of relay K establishes the circuit of the relay KA for substantial 60 periods of time while there is a corresponding reduction in the periods during which the supply of energy to the relay winding is interrupted. As a result sufficient energy is supplied to the winding of relay KA during the 65 picked-up periods of relay K to pick up the con-

tacts of relay KA and keep them picked up in the released periods of the relay K.

When relay CR is energized, the frequency of the master code is 180 cycles per minute, and accordingly the contacts of the relay TP are picked up and released at that rate. When contact 46 of relay TP picks up and releases, energy is alternately supplied to the upper and lower halves of the primary winding 48 of decoding transformer DT. As a result, an alternating current having a frequency of 3 cycles per second is induced in the secondary winding 50 of transformer DT, and is supplied therefrom through the decoding unit 180DU to the relay DR. This decoding unit, well known in the art, is constructed and arranged so that energy of a value sufficient to pick up the contact of relay DR is passed by the unit when and only when the frequency of the energy supplied thereto is that for which the unit is designed to respond.

Accordingly, at this time relay DR is energized and its contacts are picked up. Contact 52 of relay DR and contact 54 of relay BSA cooperate to supply energy to the green lamp G of signal S. This energy is supplied over a circuit which is traced from terminal B, over front contact 54 of relay BSA, front contact 52 of relay DR, and through the lamp G to terminal C. Thus, when control relay CR is picked up to denote favorable conditions in advance of section T, the supply of master code energy having a frequency of 180 cycles per minute causes signal S to display a green aspect indicating proceed.

With the equipment operating normally as described above, it is assumed that a train moving from left to right passes signal S and enters section T. The wheels and axles of the train offer a low resistance path to the impulses of master code energy, and the relay TR no longer receives sufficient energy to pick up its contacts. As a result, the contacts of relay TR release and remain released as long as the train occupies section T. Since contact 24 of relay TR remains released, the supply of energy to relays TP and FSA is cut off. After a short time interval relay FSA releases, interrupting the supply of energy to relay BSA. When contact 54 of relay BSA releases, it interrupts the circuit previously traced for supplying energy to the green lamp G of Signal S and establishes the circuit for supplying energy to the red lamp R of the signal. Contact 46 of relay TP now remains released, and as a result, energy is no longer supplied from the secondary winding 50 of transformer DT to the winding of relay DR through decoding unit 180DU and the contacts of relay DR release.

At this time, as relay TP remains released, impulses of feed back energy are no longer supplied to the section rails 1 and 2. Accordingly, relay K remains deenergized, and subsequently, relays KA and KB release. When relay KB releases, its contact 44 interrupts the supply of energy to the approach controlled circuit governed thereby.

When the train under consideration passes out of section T, relay CR will release and relay CTM will be supplied with energy by a circuit which is traced from terminal B, over back contact 10 of relay K, back contact 12 of relay CR, front contact 56 of code transmitter 75CT, and through the winding of relay CTM to terminal C. As stated above, code transmitter 75CT operates its contacts at a frequency of 75 complete cycles per minute. Accordingly, at this time relay CTM will pick up and release its contacts 75 times per

minute, and coded energy is supplied to the section rails 1 and 2 at this rate.

Relay TR will again respond to the master code energy, and relay TP will similarly operate. 5 Energy will now be supplied to relays FSA and BSA and their contacts will be picked up.

However, since contact 46 of relay TP picks up and releases 75 times per minute, the energy supplied to relay DR from transformer DT through the 180DU decoding unit is insufficient to pick up the contacts of relay DR. As a result, the yellow lamp Y of signal S is supplied with energy over front contact 54 of relay BSA and back contact 52 of relay DR.

10 15 Each time that relay TR releases, an impulse of feed back energy is supplied to the section rails 1 and 2 from battery FB during the interval between the time that contact 20 of relay TR releases and contact 22 of relay TP releases. The

20 impulses of feed back energy pick up the contacts of relay K, and when contact 10 picks up, a stick circuit for relay K is established and may be traced from terminal B, over front contact 10 of relay K, over back contact 28 of relay CR,

25 back contact 58 of code transmitter 75CT, and through the winding 32 of relay K to terminal C. When the contacts of code transmitter 75CT pick up, the stick circuit traced above is interrupted, and relay K releases, whereupon the contact 10

30 reestablishes the circuit for supplying energy to relay CTM.

The recurrent operation of the contact 40 of relay K causes relays KA and KB to be energized, and energy is again supplied to the circuit controlled by front contact 44 of relay KB.

It will be seen from the foregoing that the apparatus responds in the same manner with respect to the 75 code as it does with respect to the 180 code, with the exception, as explained above,

40 that the relay DR is not picked up during the time in which relays TR and TP are responding to 75 code, and thus causes a yellow or caution signal to be displayed at the entrance end of section T.

In addition, it will be seen that the stick circuit for the feed back track relay K is governed in such manner that the relay contacts remain picked up for the entire length of the "off" periods in the master code irrespective of the frequency of the master code.

45 After the train proceeds a sufficient distance beyond section T, relay CR picks up, and its front contacts 12 and 28 again connect the code transmitter 180CT into the circuits previously traced for supplying energy to relay CTM and to winding 32 of relay K.

50 As a result, relays TR and TP at the entrance end of the section are operated at the rate of 180 cycles per minute. Relays FSA and BSA remain energized and additionally, the relay DR will now receive sufficient energy from the decoding unit 180DU to enable it to pick up its contacts. When contact 52 of relay DR picks up, it interrupts the supply of energy to the yellow lamp Y of signal S and establishes the circuit for supplying energy to the green lamp G.

55 60 The relay K at the exit end of the section will now respond to feed back energy at the rate of 180 impulses per minute, and the relays KA and KB will remain energized.

65 70 At this time, therefore, the equipment will have been restored to its normal condition, as previously described.

If foreign potential should become present across the section rails 1 and 2 and should have such polarity and be of such value as to cause

9

the relay K to pick up, contact 10 of relay K will interrupt the circuit which supplies energy to relay CTM. Consequently, relay CTM will remain released and track relay TR will no longer receive impulses of coded energy. As a result, the relay BSA will be released and the signal S will display a red aspect, indicating that an unsafe condition exists in the section T.

Additionally, when contact 10 of relay K becomes picked up, the supply of energy to relay KB is interrupted, and relay KB releases, thereby interrupting the circuit controlled by contact 44.

At this time, as relay K is picked up its contact 10 establishes the circuit for supplying energy to the relay holding winding 32 during the released periods of the code transmitter 75CT, if relay CR is released, or of code transmitter 180CT, if the relay CR is picked up. During the picked-up periods of the contacts of the effective code transmitter the circuit of the holding winding 32 of relay K is interrupted but contact 10 of relay K does not release since it is maintained picked up by energy supplied from the track rails to the pick up or track winding 18 of the relay. During the picked-up periods of the contacts of the effective code transmitter energy is not supplied to the circuit of the relay CTM since contact 10 of relay K is picked up so the relay CTM remains released and maintains the circuit of the winding 18 of relay K.

The operation of the equipment, therefore, is such that when foreign current is present and picks up the contacts of the relay K the circuit of the relay CTM is interrupted and the contact of relay CTM is certain to remain released and maintain the circuit of the winding 18 of the relay K so that foreign current keeps the contacts of relay K picked up. As long as the contacts of relay K are picked up by foreign current the circuit of the relay holding winding 32 is recurrently established and interrupted by a contact of one of the code transmitters, but interruption of the circuit of the winding 32 cannot interfere with the circuit of the winding 18 of relay K and cannot cause release of the contacts of relay K when foreign current is present.

The control of the circuit of the holding winding 32 of relay K is such, therefore, that under normal conditions the relay contacts when picked up remain picked up for the duration of the "off" periods in the master code, and release promptly at the start of each "on" period. This insures that contact 10 of relay K will establish the circuit of relay KA for periods long enough to maintain relay KA picked up, and also insures that contact 10 of relay K will complete the circuit of relay CTM promptly upon movement of the contacts of the code transmitter so that the impulses of master code energy supplied to the track rails will not be objectionably reduced in length.

The control of the circuit of the holding winding 32 of relay K is also such that this circuit is interrupted each time the contacts of the effective code transmitter pick up. However, picking up of the code transmitter contacts does not disturb the circuit for connecting track winding 18 of relay K across the track rails, and if foreign current is present the contacts of relay K will be maintained picked up by energy supplied from the track rails to the winding 18. If relay K is maintained picked up by energy supplied to winding 18, the circuit of the relay CTM will not be established and its contact 16

10

will remain released and maintain the circuit of the winding 18 of relay K.

It will be seen, therefore, that the circuit of the winding 32 of relay K is arranged to permit the relay to release when the code transmitter picks up if conditions are proper, but not to cause it to release if conditions are not proper.

This equipment is also arranged so that if foreign potential should be present across the section rails 1 and 2 and is of such polarity and value as to cause the relay TR to pick up, and if in addition, the stick circuit governed by front contact 20 of relay TR should be ineffective, the signal S will display its red aspect.

It will be assumed that when relay TR picks up, movable contact 20 does not engage its stationary front contact, or that the wire connection to the stationary contact is broken. Under these circumstances, the relay TR will pick up, but when contact 20 interrupts the pick-up circuit which was previously traced, the supply of energy to the winding of relay TR is interrupted and the contact 20 again closes in its released position in which it reestablishes the circuit for supplying energy to the relay winding. This results in a "door-bell" action of relay TR, that is, when relay TR attempts to pick up, its contact 20 interrupts the supply of energy to the relay winding, and the relay releases and again attempts to pick up. Such repeated cycles cause the relay to operate in a manner similar to a conventional electric vibrating bell, hence the name "door-bell action." On each pick-up of contact 24 of relay TR, energy is supplied to relay TP, but relay TP requires a short time to pick up its contacts, and since relay TR immediately releases, insufficient energy is supplied to the winding of relay TP to pick up the relay contacts, and as a result the relay TP may remain released. When relay TP is released its contact 34 interrupts the supply of energy to relay FSA, and consequently, relays FSA and BSA are released and signal S will display a red aspect.

As pointed out above a short time interval is required for the contacts of relay TP to pick up after the circuit for supplying energy to the winding of relay TP is established by front contact 24 of relay TR. When the "door-bell" action of relay TR occurs the contacts of relay TR occupy their picked-up position for very short time intervals, and even if relay TP should become picked up as a result of energy supplied thereto during "door-bell" operation of the relay TR, the contacts of relay TP probably will not move to their picked-up position until after the contacts of relay TR have released. Accordingly, energy will not be supplied to relay FSA since relays TR and TP must both be picked up to establish the circuit of relay FSA.

When the relay TP picks up its contact 22 interrupts the pick up circuit for relay TR and establishes the circuit for supplying energy from battery FB through the winding of relay TR to the track rails on release of relay TR. The energy supplied from battery FB to the track rails through the winding of relay TR holds the relay contacts released and creates in the relay core flux which must be overcome before the relay contacts can be picked up again. Accordingly, if relay TP becomes picked up as a result of "door-bell" operation of relay TR, contact 22 of relay TP interrupts the pick up circuit of relay TR to prevent relay TR from picking up to establish the circuit of relay FSA.

11

Furthermore, because of the supply of energy from the battery FB through the winding of relay TR the contacts of the relay TR will not pick up for a short time subsequent to release of relay TP. As a result, if relay TP becomes picked up in response to "door-bell" operation of relay TR, the operation of relay TR is interrupted for a period so the relay TP will release and will not thereafter pick up for an interval.

If the relay TP should pick up before relay TR releases, the period during which the contacts of both of these relays are picked up is extremely short. The relay FSA is of a type the contacts of which are slow to pick up and the energy which can be supplied thereto in the intervals in which relays TR and TP are both picked up at times when the stick circuit for relay TR is defective is insufficient to pick up the contacts of relay FSA. As relay FSA remains released the relay BSA also remains released, and maintains the display of a stop indication by the signal S.

It will also be seen that if the connection to front contact 20 of relay TR is deranged, during the normal operation of the system, the relay TR will be released immediately after picking up on the supply of an impulse of master code energy with results similar to those described above in connection with the foreign current.

The equipment also operates to prevent improper energization of the relay BSA in the event the contact 24 of relay TR is defective or out of adjustment so that it simultaneously engages both of the associated stationary contacts. As long as movable contact 24 engages its upper or front stationary contact, energy is supplied to relay TP and its contacts are picked up so that energy is supplied over its front contact 34 to relay FSA. However, as relay TP is picked up its contact 36 interrupts the circuit of the relay BSA and it is certain to remain released and maintain the circuit of the red lamp R of signal S.

Referring to Fig. 2, there is shown therein a modification of the equipment located at the entrance and of section T. This modification makes it unnecessary for the track relay TR to pick up over its back contact 20, and has different operating characteristics from the arrangement shown in Fig. 1, in the event a derangement of the circuits including front contact 20 of relay TR arises.

In operation, impulses of master code energy are supplied to the track relay TR by a circuit which is traced from rail 1, through the winding of track relay TR from right to left, over back contact 22 of relay TP, and back to rail 2. When track relay TR picks up, its front contact 20 establishes a stick circuit to maintain the relay picked up. This circuit is traced from rail 1, through the winding of track relay TR, and over front contact 20 of relay TR to rail 2. When contact 24 of relay TR picks up, it establishes a circuit for supplying energy to relay TP which is traced from terminal B, over front contact 24 of relay TR, and through the blocking rectifier R1 and the winding of relay TP to terminal C. When relay TP picks up, its back contact 22 interrupts the circuit previously traced for connecting the winding of relay TR to the track rails but relay TR is now connected to the rails 1 and 2 over its own front contact 20, and will remain picked up.

Additionally, when relay TP picks up, energy is supplied to relay FSA over front contact 24 of relay TR and front contact 34 of relay TP. 70

12

At the end of the impulse of master code energy, relay TR releases and its front contact 24 interrupts the supply of energy to relays TP and FSA. Since relay TP is slow in releasing, its front contact 22 will remain closed for a short time interval and at this time feed back energy is supplied to the section rails 1 and 2 over the circuit which is traced from the positive terminal of battery FB, over back contact 20 of relay TR, through the winding of relay TR from left to right to section rail 1, and from section rail 2 over front contact 22 of relay TP to the negative terminal of battery FB. The flow of energy through the winding of relay TR is in such a direction that the contacts of this relay remain released. When relay TP releases, its contact 22 interrupts the circuit for supplying feed back energy to the section rails and reestablishes the circuit for connecting the winding of relay TR to the section rails. Additionally, when contact 24 of relay TR releases, energy is supplied to relay BSA by the circuit which is traced from terminal B, over back contact 24 of relay TR, back contact 36 of relay TP, front contact 38 of relay FSA, and through the winding of relay BSA to terminal C.

The functions controlled by contact 54 of relay BSA and contact 46 of relay TP are identical with those previously described in connection with Fig. 1 and further description of them is unnecessary.

As previously explained, when relay TR picks up, its contact 20 should connect the relay winding across the section rails independently of contact 22 of relay TP. In addition, when relay TR picks up its contact 24 establishes the circuit for supplying energy to relay TP and its contact 22 interrupts the circuit which it controls for connecting the relay TR across the track rails. If the circuit established by front contact 20 of relay TR should be defective for any reason, such as a broken wire, the supply of energy from the track rails to the winding of relay TR will be interrupted when relay TP picks up, and the contacts of relay TR will thereupon release. In the period in which the contacts of relays TR and TP are both picked up energy is supplied to relay FSA, but this period is extremely short since relay TR releases very soon after relay TP picks up.

During the time interval in which the contacts of relay TP remain picked up after relay TR releases, feed back energy is supplied to the section rails 1 and 2 by the circuit previously traced. As the source of feed back energy is the battery FB which is adjacent the track relay, the impulses of feed back energy supplied through the track relay winding are of substantially greater value than the impulses of master code energy supplied to the track relay. Since the feed back energy is of opposite polarity to the master code energy supplied to the relay winding, the effect of the feed back energy on the relay TR is to cause its contacts to remain released. When relay TP releases, if the impulse of master code energy is still in effect, the relay TR will again pick up and the cycle of operations just described will be repeated. The operation of relays TR and TP is such that the periods during which both of these relays are picked up are relatively short compared to the intervening periods during which one or both of these relays are released. Since relay FSA is of a type which is slow in picking up its contacts as well as being slow in releasing, the momentary energization of its winding during the periods in which relays TR and TP are both picked up is insufficient to cause the contacts of

13

relay FSA to pick up. Accordingly, relay FSA remains released and relay BSA is not supplied with energy at this time and its contact 54 remains released, and since the remainder of the equipment is arranged identically with that shown in Fig. 1, it will cause the signal S to display a stop aspect.

The modification shown in Fig. 3, like that shown in Fig. 1 operates to maintain relay BSA released in the event contact 24 of relay TR is defective.

Referring to Fig. 3 of the drawings, there is shown therein a stretch of railway track having track rails 1 and 2 over which it is assumed that traffic normally moves in the direction of the arrow, that is, from left to right. This track is divided into sections by the usual insulated rail joints 3. The reference characters I and II respectively designate the entrance and exit ends of the full signal block length of the track stretch, and character III designates the location of the cut which subdivides this block into a rear or approach track section 2T, and an adjoining forward track section 2AT. This cut is occasioned by a highway H which intersects the track and with which a crossing signal XS, here shown as a bell, is associated to warn the users of that highway when railway traffic approaches the intersection over the approach section 2T.

Positioned at the entrance of each of the signal block lengths of the illustrated track is the usual wayside signal S together with the control apparatus therefor. The apparatus and circuits, not shown, for the control of the signals SA and SB, which are here shown as being of the color-light type, are identical with those shown in Fig. 1 and further explanation of them is unnecessary.

In this arrangement, impulses of master code energy supplied from the exit end II of the block are repeated by the apparatus at the cut location III to control the signal at the entrance end I of the block. During the "off" periods of the master code, impulses of feed back energy are transmitted from the entrance end I of the section to the cut location III to maintain the highway crossing signals or similar apparatus inactive under all vacant conditions of the rear or approach section I-III, including times when the section III-II ahead of the cut may be occupied. When a train occupies the rear section I-III, the supply of feed back energy is cut off, and the cut section apparatus is brought into operation. When the train clears the exit end of the rear section I-III, coded energy is again supplied over the track rails to location III from location I and the equipment is thereby restored to its inactive state.

At the exit end II of the main signal block I-II, there is shown a track battery 2ATB which supplies energy to the section rails 1 and 2 of section 2AT, when contact 16 of relay CTM is picked up. The relay CTM may be controlled in a manner similar to that shown in Fig. 1, but, in any instance, it will be continuously operated at one or another of the usual plurality of distinctive code rates.

The equipment at the cut location III comprises a code following relay 2ATR, which is responsive to the impulses of coded energy supplied over the track rails 1 and 2 from the exit end II; a track battery 2TB, from which energy is supplied to the rails 1 and 2 of section 2T; a detector relay K, which responds to impulses of feed back energy supplied from the entrance end I during the "off" periods of the master code; slow release

14

code detecting relays KA and KB; and the crossing signal XS.

The equipment at the entrance end location I, comprises a code following relay TR; a code following repeater relay TP having two windings; a feed back battery 2FB; slow release code detecting relays FSA and BSA; and a coding device CT, having continuously operating contacts.

In operation, with the block I-II unoccupied, the equipment assumes its normal condition as shown in the drawings. At this time the relay CTM picks up and releases its contact 16 at a code frequency determined in the customary manner by the condition of the section in advance of signal SB. When relay CTM picks up, energy is supplied to relay 2ATR at location III by a circuit which is traced from the positive terminal of battery 2ATB, over front contact 16 of relay CTM, over rail 1 of section 2AT, through the winding of relay 2ATR, over back contact 60 of relay K, and over rail 2 of section 2AT to the negative terminal of battery 2ATB. When relay 2ATR picks up, a circuit is established for supplying energy to relay 2TR. This circuit is traced from the positive terminal of battery 2TB, over front contact 62 of relay 2ATR, through the winding of detector relay K from right to left, over rail 1 of section 2T, through the winding of relay 2TR from right to left, over back contact 22 of relay 2TP, and over rail 2 of section 2T to the negative terminal of battery 2TB.

Relays K and 2TR are of a type the contacts of which pick up when and only when energy flows through the relay windings in the direction shown by the arrows. Accordingly, at this time the contacts of relay K remain released, while the contacts of relay 2TR pick up. When relay 2TR picks up, it establishes a stick circuit for itself over its front contact 20. Additionally, front contact 24 of relay 2TR establishes a circuit for supplying energy to the winding of relay 2TP. This circuit is traced from terminal B, over front contact 24 of relay 2TR, and through the blocking rectifier R1 and the winding 64 of relay 2TP to terminal C. When relay 2TP picks up, its back contact 22 interrupts the circuit previously traced for supplying energy from the track rails to relay 2TR. However, relay 2TR will now be supplied with energy over the stick circuit established by its front contact 20 and will remain picked up for the duration of the impulse of master code energy. Additionally, when the front contact 34 of relay TP closes, energy is supplied to the winding of relay FSA by a circuit which is traced from terminal B, over front contact 24 of relay TR, over front contact 34 of relay TP, and through the blocking rectifier R2 and the winding of relay FSA to terminal C.

When relay CTM releases its contact 16, the supply of energy to relay 2ATR is interrupted, and when relay 2ATR releases, its contact 62 interrupts the supply of energy to relay 2TR, which then releases. Upon the release of contact 20 of relay 2TR, a circuit is established for supplying an impulse of feed back energy to detector relay K over the rails of section 2T. This circuit is traced from the positive terminal of battery 2FB, over back contact 20 of relay 2TR, through the winding of relay 2TR from left to right, over rail 1 of section 2T, through the winding of relay K from left to right, over back contact 62 of relay 2ATR, rail 2 of section 2T,

15

and over front contact 22 of relay 2TP to the negative terminal of battery 2FB.

The direction of flow of feed back energy is such that relay 2TR remains released, while the contacts of relay K are picked up.

The supply of energy to relay 2TP being interrupted by the release of contact 24 of relay 2TR, relay 2TP will release after a short time interval and interrupt the supply of feed back energy to relay K which thereupon releases. After a time interval, contact 16 of relay CTM picks up to supply energy from battery 2ATB to relay 2ATR, and the cycle described above is repeated.

As stated before, each time that contact 24 of relay 2TR and contact 34 of relay 2TP are picked up, energy is supplied to the winding of relay FSA. Relay FSA is slow in releasing and its contacts will remain picked up during the normal intervals during which contact 24 of relay 2TR and contact 34 of relay 2TP are released. Additionally, when contact 24 of relay 2TR and contact 36 of relay 2TP are released, relay BSA is supplied with energy by a circuit which is traced from terminal B, over back contact 24 of relay 2TR, back contact 36 of relay 2TP, front contact 38 of relay FSA, and through the winding of relay BSA to terminal C. Accordingly, while impulses of master code energy are being received, contact 54 of relay BSA is picked up, and a circuit similar to that shown and described in connection with Fig. 1 may be established over contact 54 of relay BSA to supply energy to the green lamp of signal SA.

At location III, relay K picks up and releases its contacts in response to the supply of feed back energy, and when contact 68 of relay K is picked up, energy is supplied to the winding of slow release relay KA and its contact 10 picks up. When relay K releases, energy is supplied to the winding of relay KB by a circuit which is traced from terminal B, over back contact 68 of relay K, over front contact 70 of relay KA, and through the winding of relay KB to terminal C. Relays KA and KB are sufficiently slow in releasing to bridge the intervals in which contact 68 of relay K interrupts the supply of energy to their windings, and accordingly, while relay K is responding to the impulses of feed back energy, relays KA and KB will remain picked up. At this time, contact 72 of relay KB interrupts the supply of energy to the warning signal bell XS and the bell is inactive.

It will now be assumed that a train moving from left to right passes signal SA and enters section 2T. The wheels and axles of the train shunt the master code energy to such an extent that relay 2TR does not receive sufficient energy to pick up and accordingly its contacts remain released. As contact 24 of relay 2TR remains in its released position, the supply of energy to relays 2TP and FSA is interrupted and these relays release. When contact 38 of relay FSA opens it interrupts the supply of energy to relay BSA, and when relay BSA releases, its contact 54 interrupts the supply of energy to the green lamp of signal SA and establishes the circuit for supplying energy to the red lamp of this signal.

As previously pointed out, the supply of energy to the winding 64 of relay 2TP is cut off by the release of contact 24 of relay 2TR, and as long as relay 2TR remains released, winding 64 of relay 2TP receives no energy. However, when relay FSA releases, a circuit is established

16

for supplying impulses of energy to a second winding 74 of relay 2TP. This circuit is traced from terminal B, over back contact 24 of relay 2TR, over back contact 16 of relay FSA, over front contact 18 of coding device CT, and through the winding 74 of relay 2TP to terminal C. The coding device CT is continuously connected to the local source of energy, and accordingly its contact 78 is recurrently opened and closed at a selected rate. As a result, at this time the winding 74 of relay 2TP is periodically energized, and each time winding 74 of relay 2TP is energized contact 22 picks up so that an impulse of feed back energy is supplied to rails 1 and 2 of section 2T over the circuit previously traced. However, the wheels and axles of the train assumed to be present in section 2T keep relay K from picking up.

When relay K releases and remains released, its contact 68 no longer establishes the circuit for supplying impulses of energy to relay KA, and relay KA releases, thereby interrupting the circuit governed by its front contact 10 for supplying energy to relay KB. When relay KB releases, its contact 72 establishes the circuit for supplying energy to the bell XS. Accordingly, the bell XS becomes active, warning the users of the highway H of the approach of a train.

When the train advances into section 2AT, the impulses of master code energy transmitted from location II are shunted by the wheels and axles of the train, and as a consequence relay 2ATR releases and remains released. Accordingly, contact 62 remains released and the supply of impulses of master code energy from battery 2TB to rails 1 and 2 of section 2T is cut off, while relay K is continuously connected across the rails of section 2T.

When the train vacates section 2T, the impulses of feed back energy which are at this time supplied to the rails 1 and 2 of section 2T by operation of relay TP by the circuit previously traced, are effective to operate relay K, and as a result the relays KA and KB are again energized. When contact 72 of relay KB picks up, it interrupts the supply of energy to the bell XS, which then becomes inactive.

As long as any part of the train remains in the section 2AT, the winding of relay K remains continuously connected across the rails of the section 2T, since contact 62 of relay 2ATR then continuously occupies its released position. When the rear of the departing train clears the exit end of the forward section 2AT, the rails of that section once more transmit master code energy from the battery 2ATB to the code following relay 2ATR at location III.

At this time relay K is responding to feed back coded energy supplied from location I and governed by the circuits including contact 78 of coding device CT. However, during the periods that relay K is released between impulses of feed back energy, its back contact 60 establishes the connection of relay 2ATR to the rails 1 and 2 of section 2AT, and relay 2ATR will pick up when supplied with an impulse of master code energy from location II. Contact 62 of relay 2ATR will then establish the circuit for supplying energy from the battery 2TB to the rails 1 and 2 of section 2T, and relay 2TR at location I will respond to the energy by picking up its contacts. When contact 24 of relay 2TR picks up, energy is supplied to winding 64 of relay 2TP, and when relay 2TP picks up, its contact 34 completes the circuit for supplying energy to

relay FSA and its contacts pick up so that contact 76 interrupts the circuit governed by code transmitter CT for supplying energy to winding 74 of relay 2TP. The relay 2TP now operates in the manner originally described when the block I-II was vacant, and impulses of feed back energy are supplied to relay K during the "off" periods of the master code energy, thus retaining the relays KA and KB picked up and rendering the bell XS ineffective.

Additionally, continuous operation of relays 2TR and 2TP will cause relay BSA to become energized. The equipment is now restored to its normal condition as originally described.

The arrangement of equipment shown in Fig. 3 embodying my invention is particularly advantageous in that the effects of foreign energy which might exist in the section rails are prevented from creating a dangerous condition. It will be assumed that a train is present in the approach section 2T, proceeding towards the highway crossing at location III. If a foreign potential of the proper polarity and magnitude exists across the rails 1 and 2, the relay K will pick up. However, when contact 60 of relay K picks up, it interrupts the connection of relay 2ATR to the rails of section 2AT, and relay 2ATR remains released and its contact 62 will connect the winding of relay K across the rails of section 2T continuously. Accordingly, the foreign energy will retain relay K picked up and its contact 63 will interrupt the supply of energy to relay KB, which will release and thereby cause the bell XS to operate, as is proper at this time.

If foreign energy should pick up the relay K, with the result described above, at a time when the block I-II is vacant, relay 2ATR will remain continuously released because its circuit is interrupted by contact 60 of relay K. Accordingly, the supply of impulses of master code energy from battery 2TB to relay 2TR will be cut off, and the relays FSA and BSA will release, with the result that the signal SA will display a red aspect, denoting a dangerous condition existing in the block I-II. Although after release of relay FSA the relay 2TP is operated by the circuit including contact 78 of coding device CT, the impulses of feed back energy supplied as a result of operation of relay TP only serve to maintain the relay K picked up.

Referring to Fig. 4, I have there represented a somewhat modified form of entrance end facilities which are suitable for use with the arrangement shown in Fig. 3 and may be substituted for the apparatus represented at location I in that figure. These modified facilities of Fig. 4 are generally the equivalent to the corresponding entrance end facilities of Fig. 3, except that it will be assumed that the block I-II is a part of a block signaling system, and that section IT is another block extending rearwardly from location I. Also it will be assumed that the master code may have one or the other of two frequencies, 75 cycles per minute if the immediate block in advance is occupied, and 180 cycles per minute if the next block in advance is additionally vacant.

Contact 66a of relay 2TP and contact 54a of relay BSA govern circuits (not shown) to provide control of signal SA which is similar to that shown in Fig. 1.

During normal operation of the equipment, with the track section 2T vacant, the apparatus functions in substantially the same manner as previously described in connection with Figs. 1

and 2 and a detailed explanation and tracing of the various circuits is unnecessary.

Section IT is provided with a coded track circuit for controlling a signal (not shown) in the rear, and as long as block I-II is occupied master code energy will be supplied to section IT 75 times per minute, and when block I-II is unoccupied master code energy will be supplied to section IT 180 times per minute. Code transmitting relay ICTM, therefore, is operated 75 times per minute or 180 times per minute, according as block I-II is occupied or unoccupied.

When the block I-II is unoccupied, relay BSA is picked up and relay ICTM is supplied with energy by a circuit which is traced from terminal B over contact 82 of coding device 180CT, over front contact 84 of relay BSA, and through the winding of relay CTM to terminal C.

When the block I-II is occupied, relay BSA is released and its contact 84 interrupts the circuit governed by contact 82 of coding device 180CT for supplying energy to relay ICTM. However, at this time relay 2TR is released, and a circuit is thereby established to supply energy to relay ICTM. This circuit is traced from terminal B, over back contact 24 of relay 2TR, over contact 88 of coding device 75CT, over back contact 84 of relay BSA, and through the winding of relay ICTM to terminal C.

Additionally, during occupancy of block I-II impulses of feed back energy are supplied to rails 1 and 2 of section 2T to discontinue operation of the crossing signal when the rear of the train clears that section 2T, as explained in connection with Fig. 3. At this time relay 2TP is supplied with energy by the circuit which is traced from terminal B, over back contact 24 of relay 2TR, over contact 88 of coding device 75CT, over back contact 90 of relay ICTM, over back contact 76 of relay FSA, and through the winding 74 of relay 2TP to terminal C.

Accordingly, each time contact 88 of coding device 75CT closes, relay 2TP is picked up, but in a very short time interval relay ICTM will pick up, interrupting the supply of energy to winding 74 of relay 2TP. It will be seen, therefore, that the relay 2TP is operated to provide impulses of feed back energy having a very short duration. These impulses, though short, are adequate to operate the relay K at the exit end of section 2T to energize the relays KA and KB and discontinue operation of the crossing signal. The use of short impulses of feed back energy during the time that block I-II is occupied is advantageous in that it allows a longer "off" period during which when the master code energy is again supplied from the exit end of the block, the track relay 2ATR may pick up to regain its control of section 2T.

Although I have herein shown and described only four forms of signaling apparatus embodying my invention, it is understood that various changes and modifications may be made therein within the scope of the appended claims without departing from the spirit and scope of my invention.

Having thus described my invention, what I claim is:

1. In means for indicating at both ends of a section of railway track the condition of occupancy of said section, in combination, a first code following track relay at the first end of said track section and a second code following track relay at the second end of said track section, each of said track relays having front and back contacts

closed respectively according as the relay is energized by energy supplied to the relay winding over the section rails or is deenergized, a transmitter relay having a contact movable between a first position in which it effectively connects the winding of said first track relay across the rails of said section and a second position in which it connects a source of energy across said section rails, a code transmitter having contacts movable between a first and a second position at a selected rate and occupying each of their two positions for substantially equal time intervals, an operating circuit including a first position contact of said code transmitter and a back contact of said first track relay for moving the contact of said transmitter relay from its first to its second position, code detecting means responsive to alternate establishment of circuits governed over front and back contacts of said first track relay, means for prolonging the picked-up periods of said first track relay to thereby facilitate operation of said code detecting means without interfering with the control by said track relay of the circuit of said transmitter relay, said means comprising a circuit including a front contact of said first track relay and a second position contact of said code transmitter, a repeater relay to which energy is supplied over a front contact of said second track relay, a circuit including a back contact of said repeater relay for connecting the winding of said second track relay across said section rails, a circuit including a front contact of said second track relay for also connecting the winding of said second track relay across said section rails, a circuit including a front contact of said repeater relay and a back contact of said second track relay for connecting a source of energy across said track rails, and means for detecting operation of said second track relay, said means comprising a slow acting relay energized by a circuit including front contacts of said second track relay and said repeater relay in series, and a slow release relay energized by a circuit including back contacts of said second track relay and said repeater relay and a front contact of said slow acting relay in series.

2. In combination, a section of track, a first code following track relay located at the first end of said section and having front and back contacts closed respectively according as the relay is energized or deenergized, a transmitting relay having a contact movable between a first position in which it effectively connects said first code following relay across the rails of said track section and a second position in which it connects a first source of current across said track rails for supplying master code energy, a coding device having a contact operated between a first and a second position, an operating circuit including a back contact of said first code following relay and a first position contact of said coding device for moving the contact of said transmitting relay from its first to its second position, said coding device operating in such manner that the transmitting relay contact normally occupies its first position for predetermined time intervals, a second code following track relay located at the second end of said section and having front and back contacts closed respectively according as the relay is energized by master code energy supplied over the track rails from said first source of current or is deenergized, a code following repeater relay to which energy is supplied over a circuit including a front contact of said second code following track relay, said repeater relay

having a release delay shorter than the period between the impulses of said master code energy, a pick-up circuit including a back contact of said repeater relay for connecting said second track relay across the rails of said track section, a stick circuit including a front contact of said second track relay for also connecting said second track relay across the rails of said track section, a circuit including a back contact of said second track relay and a front contact of said repeater relay for connecting a source of feed back energy across the rails of said track section, means for detecting operation of said second track relay by master code energy supplied over the rails of said section, said means comprising a slow acting relay to which energy is supplied over a circuit including front contacts of said second track relay and said repeater relay in series, and a slow release relay to which energy is supplied over a circuit including back contacts of said second track relay and said repeater relay and a front contact of said slow acting relay in series, and a circuit governed by a contact of said slow release relay, a circuit including a front contact of said first code following track relay and a second position contact of said coding device for supplying energy to a winding of said first code following track relay to thereby prolong the picked-up periods of the contacts of said first code following track relay without interfering with the control by said first code following track relay of the operating circuit for said transmitting relay, a second detecting means for detecting the code following operation of said first code following track relay, and a circuit governed by said second detecting means.

3. In a coded track circuit of the feed back type, in combination, a section of track, means for supplying to the rails of said section at the first end thereof impulses of master code energy, a code following track relay located at the second end of said section, a code following repeater relay to which energy is supplied over a circuit including a front contact of said track relay, said repeater relay having a release delay shorter than the period between the impulses of said master code energy, a pick-up circuit including a back contact of said repeater relay for connecting said track relay across the rails of said track section, a stick circuit including a front contact of said track relay for also connecting said track relay across the rails of said track section, a circuit including a back contact of said track relay and a front contact of said repeater relay for connecting a source of feed back energy across the rails of said track section, and means for detecting operation of said track relay by master code energy supplied over the rails of said track section, said means comprising a slow acting relay to which energy is supplied over a circuit including front contacts of said track relay and of said repeater relay in series, and a slow release relay to which energy is supplied over a circuit including back contacts of said track relay and of said repeater relay and a front contact of said slow acting relay in series, and a circuit governed by a contact of said slow release relay.

4. In a coded track circuit of the feed back type, in combination, a section of track, means for supplying to the rails of said section at the first end thereof impulses of master code energy, a code following track relay located at the second end of said section, a code following repeater relay to which energy is supplied over a circuit including a front contact of said track relay, said

repeater relay having a release delay shorter than the period between the impulses of said master code energy, a pick-up circuit including a back contact of said repeater relay for connecting said track relay across the rails of said track section, a stick circuit including a front contact of said track relay for also connecting said track relay across the rails of said track section, a circuit including a back contact of said track relay and a front contact of said repeater relay for connecting a source of feed back energy across the rails of said track section, and means for detecting operation of said track relay by master code energy supplied over the rails of said track section, said means comprising a first auxiliary relay to which energy is supplied over a circuit including front contacts of said track and repeater relays in series, and a second auxiliary relay to which energy is supplied over a circuit including back contacts of said track and repeater relays and a front contact of said first auxiliary relay in series, said first auxiliary relay being of a type the contacts of which are slow enough in picking up to become picked up only when the circuit for supplying energy thereto is established for time intervals substantially longer than the time required for said track relay to release in the event that its stick circuit fails to close, said auxiliary relays being slow enough in releasing to remain picked up during normal code following operation of said track relay, and a circuit governed by a contact of said second auxiliary relay.

5. In combination, a section of track, a first code following track relay located at the first end of said section and having front and back contacts closed respectively according as the relay is energized or deenergized, a transmitting relay having a contact movable between a first position in which it effectively connects said first code following relay across the rails of said track section and a second position in which it connects a first source of current across said track rails, a coding device having a contact operated between a first and a second position, an operating circuit including a back contact of said first code following relay and a first position contact of said coding device for moving the contact of said transmitting relay from its first to its second position, said coding device operating in such manner that the transmitting relay contact normally occupies its first position for predetermined time intervals, a second code following track relay located at the second end of said section and having a contact biased to a released position from which it is moved to a picked-up position by master code energy supplied over the track rails from said first source of current, means governed by said second code following track relay and operative upon each movement of the contacts of said relay to their released position to connect a second source of energy across said track rails for a period substantially shorter than said predetermined time intervals, a circuit including a front contact of said first code following track relay and a second position contact of said coding device for supplying energy to a winding of said first code following track relay to thereby prolong the picked-up periods of the contacts of said first code following track relay without interfering with the control by said first code following track relay of the operating circuit for said transmitting relay, detecting means for detecting the code following operation of said first code following track relay, and a circuit governed by said detecting means.

6. In combination, a section of track, a first code following relay located at the first end of said section and having a contact biased to a released position from which it is moved to a picked-up position on the supply of energy to a winding of the relay, a transmitting relay having a contact movable between a first position in which it effectively connects said first code following relay across said track rails and a second position in which it connects a first source of current across said track rails, a first coding device having a contact operated between a first and a second position at a selected rate, a second coding device having a contact operated between a first and a second position at a different rate, a control relay having contacts movable between a first and a second position and governed by traffic conditions affecting said section, a first operating circuit including a contact of said first code following relay closed in its released position, a first position contact of said control relay and a first position contact of said first coding device for moving the contact of said transmitting relay from its first to its second position, 25 a second operating circuit including a contact of said first code following relay closed in its released position, a second position contact of said control relay, and a first position contact of said second coding device for also moving the contact of said transmitting relay from its first to its second position, said coding devices operating their contacts so that the contacts remain in their first and their second positions for a predetermined time interval so that the transmitting relay contact normally occupies its first position for predetermined time intervals, a second code following relay located at the second end of said section and having a contact biased to a released position from which it is moved to a picked-up position by energy supplied over the track rails from said first source of current, means governed by said second code following relay and operative upon each movement of the contacts of said relay to their released position to connect 35 a second source of energy across said track rails for a period substantially shorter than said predetermined time intervals, a first stick circuit including a contact of said first code following relay closed in its picked-up position, a first position contact of said control relay and a second position contact of said first coding device, a second stick circuit including a contact of said first code following relay closed in its picked-up position, a second position contact of said control relay and a second position contact of said second coding device, said stick circuits supplying energy to a winding of said first code following relay without interfering with the control of the operating circuits for said transmitting relay by said 40 first code following relay, detecting means for detecting the code following operation of said first code following relay, and a circuit governed by said detecting means.

7. In combination, a stretch of railway track having adjacent rearward and forward sections through which traffic normally moves in the order named, means for supplying impulses of master code energy to the track rails at the exit end of said forward section, a first code following track relay at the entrance end of said forward section, a second code following track relay of the polar biased type and a first source of energy located at the exit end of said rearward section, the winding of said first track relay being connected across the rails of said forward section

by a circuit including a back contact of said second track relay, means including a front contact of said first track relay for supplying impulses of master code energy from said first source to the rails of said rearward section according as said first track relay is operated by impulses of master code energy received over the rails of said forward section, means including a back contact of said first track relay for connecting the winding of said second track relay across the rails of said rearward section during the intervals between impulses of master code energy, means for detecting the operation of said second track relay, a circuit controlled by said detecting means, a third code following track relay located at the entrance end of said rearward section, a code following repeater relay having a first and a second winding, a circuit including a front contact of said third track relay for supplying energy to the first winding of said repeater relay, said repeater relay having a release delay shorter than said intervals between impulses of master code energy, a pick-up circuit including a back contact of said repeater relay for connecting said third track relay across the rails of said rearward section, a stick circuit including a front contact of said third track relay for also connecting said third track relay across the rails of said track section, a circuit including a back contact of said third track relay and a front contact of said repeater relay for connecting a source of feed back energy across the rails of said rearward track section, means for detecting operation of said third track relay by master code energy supplied over the rails of said rearward track section, said means comprising a slow acting relay to which energy is supplied over a circuit including front contacts of said third track relay and of said repeater relay in series, and a slow release relay to which energy is supplied over a circuit including back contacts of said third track relay and of said repeater relay and a front contact of said slow acting relay in series and a circuit governed by a contact of said slow release relay, and means for causing operation of said repeater relay when said third track relay is released to thereby cause impulses of energy to be delivered to the rails of said rearward section when master code energy is not supplied over the section rails, said means comprising a coding device having recurrently operated contacts and a circuit including back contacts of said third track relay and of said slow acting relay and a contact of said coding device in series for supplying energy to the second winding of said repeater relay.

8. In combination, a stretch of railway track including adjacent rearward and forward sections through which traffic normally moves in the order named, means for supplying impulses of master code energy to the track rails at the exit end of said forward section, a first code following track relay at the entrance end of said forward section, a second code following track relay of the polar biased type and a first source of energy located at the exit end of said rearward section, the winding of said first track relay being connected across the rails of said forward section by a circuit including a back contact of said second track relay, circuit means including a front contact of said first track relay for supplying impulses of master code energy from said first source to the rails of said rearward section according as said first track relay is operated by impulses of master code energy

received over the rails of said forward section, means including a back contact of said first track relay for connecting the winding of said second track relay across the rails of said rearward section during the intervals between impulses of master code energy, means for detecting the operation of said second track relay, a circuit controlled by said detecting means, a third code following track relay located at the entrance end of said rearward section, a code following repeater relay having a first and a second winding, a circuit including a front contact of said third track relay for supplying energy to the first winding of said repeater relay, said repeater relay having a release delay shorter than said intervals between impulses of master code energy, a pick-up circuit including a back contact of said repeater relay for connecting said third track relay across the rails of said rearward section, a stick circuit including a front contact of said third track relay for also connecting said third track relay across the rails of said track section, a circuit including a back contact of said third track relay and a front contact of said repeater relay for connecting a source of feed back energy across the rails of said rearward track section, means for detecting operation of said third track relay by master code energy supplied over the rails of said rearward track section, said means comprising a slow acting relay to which energy is supplied over a circuit including front contacts of said third track relay and of said repeater relay in series, and a slow release relay to which energy is supplied over a circuit including back contacts of said third track relay and of said repeater relay and a front contact of said slow acting relay in series and a circuit governed by a contact of said slow release relay, and means for causing operation of said repeater relay when said third track relay is released, to thereby cause impulses of energy to be delivered to the rails of said rearward section when master code energy is not supplied over the section rails, said means comprising a coding device having recurrently operated contacts, a coding relay supplied with energy by a circuit including a contact of said coding device and back contacts of said slow release relay and of said third track relay in series, and a circuit including back contacts of said third track relay and of said slow acting relay in series, and also including a contact of said coding device and a back contact of said coding relay for supplying to the second winding of said repeater relay impulses of energy having a substantially shorter duration than said intervals between the impulses of master code energy.

9. In a coded track circuit of the feed back type, in combination, a section of track, means for supplying to the rails of said section at the first end thereof impulses of master code energy of a given polarity, a code following track relay located at the second end of said section, said code following track relay being of the type which is responsive when and only when energy of one polarity is supplied to the winding of the relay, a code following repeater relay to which energy is supplied over a circuit including a front contact of said track relay, said repeater relay having a release delay shorter than the period between the impulses of said master code energy, a pick-up circuit including a back contact of said repeater relay for connecting said track relay across the rails of said track section, a stick circuit including a front contact of said track relay

for also connecting said track relay across the rails of said track section, said pick-up and stick circuits being arranged so that the impulses of said master code energy supplied over the circuits to said track relay are of the polarity required to cause operation of the track relay, a circuit including a back contact of said track relay and a front contact of said repeater relay for connecting a source of feed back energy across the rails of said track section, and means for detecting operation of said track relay by master code energy supplied over the rails of said track section, said means comprising a slow acting relay to which energy is supplied over a circuit including front contacts of said track relay and of said repeater relay in series, and a slow release relay to which energy is supplied over a circuit including back contacts of said track relay and of said repeater relay and a front contact of said slow acting relay in series, and a circuit governed by a contact of said slow release relay.

10. In a coded track circuit of the feed back type, in combination, a section of track, means for supplying to the rails of said section at the first end thereof impulses of master code energy of a given polarity, a code following track relay located at the second end of said section, said code following track relay being of the type which is responsive when and only when energy of one polarity is supplied to the winding of the relay, a code following repeater relay to which energy is supplied over a circuit including a front contact of said track relay, said repeater relay having a release delay shorter than the period between the impulses of said master code energy, 30 a pick-up circuit including a back contact of said repeater relay for connecting said track relay across the rails of said track section, a stick circuit including a front contact of said track relay for also connecting said track relay across the rails of said track section, said pick-up and stick circuits being arranged so that the impulses of said master code energy supplied over the circuits to said track relay are of the polarity required to

cause operation of the track relay, a circuit including a back contact of said track relay and a front contact of said repeater relay for connecting a source of feed back energy across the rails of said track section, and means for detecting operation of said track relay by master code energy supplied over the rails of said track section, said means comprising a first auxiliary relay to which energy is supplied over a circuit including front contacts of said track and repeater relays in series, and a second auxiliary relay to which energy is supplied over a circuit including back contacts of said track and repeater relays and a front contact of said first auxiliary relay in series, said first auxiliary relay being of a type the contacts of which are slow enough in picking up to become picked up only when the circuit for supplying energy thereto is established for time intervals substantially longer than the time required for said track relay to release in the event that its stick circuit fails to close, said auxiliary relays being slow enough in releasing to remain picked up during normal code following operation of said track relay, and a circuit governed by a contact of said second auxiliary relay.

ARTHUR L. JEROME.
